UNITED STATES PATENT OFFICE.

ED JACKSON, OF THURBER, TEXAS.

MANUALLY-OPERATED COAL-MINING MACHINE.

1,309,477.

Specification of Letters Patent,

Patented July 8, 1919.

Application filed April 4, 1916. Serial No. 88,819.

To all whom it may concern:

Be it known that I, ED JACKSON, a citizen of the United States, residing at Thurber, in the county of Erath and State of Texas, 5 have invented certain new and useful Improvements in Manually-Operated Coal-Mining Machines; and I do hereby declare the following to be a full, clear and exact description of the invention, such as will 10 enable others skilled in the art to which it appertains to make and use the same.

The invention relates to coal mining machines.

The object of the present invention is to 15 improve the construction of coal mining machines and to provide a simple, practical and efficient coal mining machine adapted to be manually operated and capable of enabling a miner to mine a much greater 20 amount of coal in considerably less time and with less labor than is possible with an ordinary hand pick.

A further object of the invention is to 25 provide a manually operated mining machine of this character adapted to be operated with the miner in an upright position and capable of cutting coal close to the bottom of the floor of the tunnel or other place where the coal is being mined, thereby 30 obviating the necessity of a miner lying upon cold wet surfaces and using a pick.

With these and other objects in view the invention consists in the construction and 35 novel combination and arrangement of parts hereinafter fully described, illustrated in the accompanying drawings and pointed out in the claims hereto appended, it being understood that various changes in the form, proportion and minor details of construction 40 may be resorted to without departing from the spirit or sacrificing any of the advantages of the invention.

In the drawings

Figure 1 is a plan view of a manually 45 operable mining machine constructed in accordance with this invention,

Fig. 2 is a vertical longitudinal sectional view of the same,

Fig. 3 is a side elevation of the lower portion of the mining machine,

Fig. 4 is an end elevation of the mining machine,

Fig. 5 is a detail vertical sectional view illustrating the construction of the gearing of the feed mechanism and the means for throwing the feeding mechanism out of operation,

Fig. 6 is an enlarged detail sectional view through the horizontal cutting wheel.

Fig. 7 is a detail sectional view illustrating the manner of mounting the lower end of the vertical shaft,

Fig. 8 is a horizontal sectional view through the lower portion of the stand illustrating the arrangement of the guides of the feeding chain,

Fig. 9 is a detail view of the pulley of the crank shaft for operating the flexible connection for returning the oscillatory arm to its initial position.

Fig. 10 is a detail view of an adjusting device for forming an extension of the top screw.

Like numerals of reference designate corresponding parts in the several figures of the drawings.

In the accompanying drawings in which is illustrated the preferred embodiment of the invention, the machine comprises in its construction, a stand or frame consisting of a base 1, spaced vertical sides 2 and 3, and a connecting top portion 4, the base and top portion being designed to be provided with suitable screws 5 and 6 by means of which the frame is firmly anchored in a tunnel and while a single screw is shown at the top and bottom of the frame, any number may of course be employed for this purpose and the frame may be constructed of any suitable material to secure the desired strength and stability without rendering the machine excessively heavy for one man to handle in moving it from one place or point to another. The base is provided at its rear portion with a suitable handle 7 to enable it to be conveniently dragged along when it is necessary to move the machine.

The base of the machine is rounded at the left front corner at 8 and it has pivotally mounted on it a horizontally oscillatory arm 100

- 9 extending forwardly from the front of the base and pivoted at its rear end by a sleeve 10 which is also adapted to form a bearing for the lower end 11 of a vertical shaft 12.
- 5 The arm 9 which extends forwardly from the front of the base is adapted to swing horizontally from the front central position to the left hand side of the base to carry a horizontally disposed rotary cutting wheel 13 through the coal to be mined and the said oscillatory arm is preferably composed of upper and lower sections 14 and 15 which are angularly bent as shown to clear the wheel and also to arrange their rear portions 15 contiguous to each other to enable such portions to be rigidly secured together but the said arms may be constructed in any desired manner to correspond with the construction of the rotary cutting wheel.
- 20 The arm is also provided with a laterally extending shield or fender 16 located in advance of the rounded front corner of the base and adapted to prevent the cutting wheel from throwing the coal dust against the machine.

The rotary cutting wheel which is mounted on a vertical shaft or axle 17 preferably consists of a rim 18 and radial spokes 19 which are preferably formed integral with 30 a hub 20. The rim 18 is provided with perforations 21 for the reception of shanks 22 of picks 23 extending outwardly from the periphery of the wheel and curved slightly in the direction of the rotation of the same 35 and adapted to cut into the coal in a manner similar to an ordinary pick. The shanks 22 are threaded for the reception of nuts 24 and the picks which are adapted to be readily removed to enable them to be conveniently sharpened and pointed are arranged to cut a kerf of sufficient width or size to enable the wheel to rotate within the same without binding against the walls thereof. The picks or cutters are shown 40 arranged in three rows in staggered relation but they may be arranged in any other desired manner as will be readily understood, and cutters of various shapes and sizes may of course be employed. The rotary cutting 45 wheel which is preferably supported by a ball bearing 25 is equipped at its upper face with a sprocket wheel 26 suitably fixed to the cutting wheel and meshing with a sprocket chain 27 of any preferred construction extending from the front sprocket wheel 26 to a rear sprocket wheel 28 that is mounted on the lower portion of the upright shaft 12. The sides or flights of the sprocket chain are guided by front and rear 50 pulleys 29 and 30 arranged in pairs, the chain passing beneath the front pulleys and over the rear pulleys but any other suitable arrangement of guiding means may be employed and other forms of gearing may be

used for transmitting motion from the vertical shaft to the rotary cutting wheel.

The vertical shaft has keyed or otherwise secured to it a horizontal gear wheel 31 having teeth at its lower face meshing with vertical gear wheels or pinions 32 and 33, bevel gears being preferably provided as shown. The bevel gear or pinion 32 is mounted on a horizontal crank shaft 34 and the other bevel gear or pinion 33 is mounted on a horizontal shaft 35 arranged in transverse alignment with the shaft 34 and a fly or balance wheel 36. The shafts 34 and 35 are journaled in suitable bearings of the opposite sides of the frame or stand and the said shaft 34 is equipped at its outer portion with a pulley 37 and a double crank 38 but any other suitable operating device may of course be provided. The bevel crank enables the crank shaft 34 to be rotated with the use of both the hands of the operator 80 and the balance wheel 36 which is located at the opposite side of the frame of the machine, assists the operation of the same and secures a steady uniform motion and at the same time relieves the operator of the jars incident to the cutting operation. The gearing may be of any desired diameters to secure the desired speed of the rotary cutting wheel which is designed to be rapidly rotated so that its rapid rotation combined 95 with the weight of the wheel and the momentum of the fly or balance wheel will enable an easy cutting operation to be effected.

The oscillatory arm is provided at the left hand side adjacent to the inner end of the fender with a bail 39 to which is connected the front end of a feed chain 40 or other suitable flexible connection which extends rearwardly across a vertical guide roller 41 and over a horizontal guide roller 42 and around a rear vertical guide pulley or roller 43 mounted on the rear portion of the base. The feed chain extends forwardly from the rear vertical guide pulley or roller 43 to a horizontal shaft 44 extending across the frame of the machine and constituting a drum or windlass around which the feed chain is wound during the cutting operation of the machine to swing the cutting wheel laterally and advance the same into the coal from the full line position illustrated in Fig. 1 of the drawings to the dotted line position shown in the said figure.

The horizontal winding shaft of the feeding mechanism is intermittently rotated by 120 gearing comprising combined gear and ratchet wheels 45 and 46 mounted respectively on the winding shaft and on a stub shaft 47. The gear wheel 46 which is located above the gear wheel 45 is actuated by a pawl or dog 48 which is connected with the strap 49 of an eccentric 50. The actuating pawl or dog 48 which is arranged at

an inclination is located above the ratchet wheel and while it is maintained in engagement with the combined ratchet and gear wheel 46 by gravity, a spring may be employed if desired and in the downwardly or rearward movement of the pawl or dog, it advances the wheel 46 the distance of one tooth, the feeding mechanism being held against retrograde movement by a check pawl 51 located in rear of the lower combined gear and ratchet wheel 45 extending upwardly from a pivot 52 and having an engaging upper end or tooth and maintained in engagement with the said wheel 45 by a coiled spring 53. When it is desired to throw the feed mechanism out of operation to return the cutting wheel to its initial position, this result is accomplished by mechanism comprising a lever 54 fulcrumed at 55 on one side of the frame and pivoted at its lower end at 56 to the lower end of an inclined link 57 which is connected at its upper end at 58 to one end of a bell crank lever 59. The bell crank lever is fulcrumed at its angle at 60 and one of its arms extends downwardly and forwardly from the pivot and its other arm extends rearwardly to a point beneath the lower portion of the actuating pawl or dog 48. The operating lever 54 extends in advance of the engaging portion or upper end of the check pawl 51 and when the operating lever is actuated to swing its lower arm rearwardly, it carries the check pawl out of engagement with the lower wheel 45 and moves the rearwardly extending arm of the bell crank lever upwardly to lift the actuating pawl out of engagement with the wheel 46. The parts are adapted to be locked in this position by a catch consisting of a hook 61 pivotally mounted on the adjacent side of the frame of the machine and adapted to swing into and out of engagement with the upper arm of the operating lever. This will prevent the bell crank lever from returning to its normal position and will hold the operating lever in position for maintaining the check pawl out of engagement. As soon as the catch is disengaged from the operating lever the pawls will return to their engaging positions. The cutting wheel is returned to its initial position by a chain 62 connected at its front end with the oscillatory arm and guided by pulleys 63 and 64 and extending to the pulley 37 of the crank shaft. The pulley 37 of the crank shaft is provided with a socket 65 and the crank shaft is adapted to be rotated to wind the right hand chain around the pulley 37 which is grooved at its periphery to receive the said chain. This will enable the oscillatory arm and the cutting wheel to be quickly returned to their initial positions. In Fig. 10 of the drawing is illustrated an adjusting device to form an extension of the screw 5. The extension

device consists of male and female telescopic sections 66 and 67 and a set screw 68. The tubular or female member carries an engaging point 69 at its outer end and the rod or male member 66 is provided in its inner end with a socket or recess to be engaged by the screw 5.

What is claimed is:—

1. A mining machine of the class described including a frame, a pivotally mounted horizontally movable arm extending from the frame, a rotary cutting wheel carried by the arm, gearing for rotating the cutting wheel, a winding shaft having a flexible connection connected with the arm for moving the same laterally to feed the wheel, a pair of combined gears and ratchet wheels, one of the said wheels being mounted on the winding shaft, a check pawl engaging such wheel, an eccentric operated by the gearing for actuating the cutting wheel and having a strap and an actuating pawl or dog connected with the eccentric strap and arranged to engage and actuate the other combined gear and ratchet wheel for intermittently rotating the winding shaft, a bell crank having one arm arranged to lift the actuating pawl out of engagement, an operating lever arranged to move the check pawl out of engagement and means for connecting the operating lever with the bell crank lever.

2. A mining machine of the class described including a frame, a pivotally mounted horizontally movable arm extending from the frame, a rotary cutting wheel carried by the arm, gearing for rotating the cutting wheel, a winding shaft having a flexible connection connected with the arm for moving the same laterally to feed the wheel, a pair of combined gears and ratchet wheels, one of the said wheels being mounted on the winding shaft, a check pawl engaging such wheel, an eccentric operated by the gearing for actuating the cutting wheel and having a strap and an actuating pawl or dog connected with the eccentric strap and arranged to engage and actuate the other combined gear and ratchet wheel for intermittently rotating the winding shaft, a bell crank having one arm arranged to lift the actuating pawl out of engagement, an operating lever arranged to move the check pawl out of engagement and means for connecting the operating lever with the bell crank lever, and a catch arranged to hold the actuating pawl or dog and the bell crank lever against movement.

3. A mining machine of the class described including a pivotally mounted oscillatory arm, a rotary cutting wheel mounted on the arm and carried by the same, means for rapidly rotating the cutting wheel, feed mechanism connected with the arm and adapted to move the same in one direction to feed the

cutting wheel, a power shaft adapted to simultaneously operate said means and said feed mechanism, means adapted to be operated by said shaft for moving the arm in the opposite direction to return the cutting wheel to its initial position, and means for disconnecting said feed mechanism from the power shaft to permit the arm to be moved

in said opposite direction by said returning means.

In testimony whereof I affix my signature in presence of two witnesses.

ED JACKSON.
